UNITED STATES PATENT OFFICE.

UNION A. GREGG, OF PARIS, ILLINOIS.

GATE.

SPECIFICATION forming part of Letters Patent No. 643,325, dated February 13, 1900.

Application filed March 30, 1899. Serial No. 711,085. (No model.)

To all whom it may concern:

Be it known that I, UNION A. GREGG, a citizen of the United States, residing at Paris, in the county of Edgar and State of Illinois, have invented a new and useful Gate, of which the following is a specification.

The invention relates to improvements in gates.

One object of the present invention is to improve the construction of gates and to provide simple and efficient means for enabling a gate to be readily opened at a distance from it without dismounting or leaving a vehicle.

A further object of the invention is to cushion the opening and closing movement of a gate and to enable the latter to be operated to open or close it completely by a single movement of an operating-lever.

The invention consists in the construction and novel combination and arrangement of parts, as hereinafter fully described, illustrated in the accompanying drawings, and pointed out in the claims hereto appended.

In the drawings, Figure 1 is a perspective view of a gate constructed in accordance with this invention. Fig. 2 is a vertical sectional view of the inner portion of the gate. Fig. 3 is a detail sectional view of the inner portion of the gate.

Like numerals of reference designate corresponding parts in all the figures of the drawings.

1 designates a swinging gate provided with a tubular inner end bar 2, and preferably composed of a tubular frame having its top and bottom portion supported by vertical bars 3, perforated for the reception of wires 4, which form the body portion of the gate. The tubular end bar 2 is arranged in an eye 4^a of the upper portion of a hinge-post 5, and the lower end of the bar 2 is provided with a ball-bearing. This ball-bearing, which enables the gate to swing freely, consists of a ball-cup 6, mounted upon the post 5, and a bearing-cone 7, arranged within the lower end of the tubular bar 2 and supported upon antifriction-balls 8. The lower end of the tubular end bar 2 is enlarged to form a cap for the bearing, and the cup is provided with a centrally-arranged vertically-disposed stem 9, extending through the bearing-cone and forming the lower pintle of the gate. The stem 9 is pro-

vided with a horizontal extension 10, passing through a perforation of the hinge-post, and threaded to receive nuts 11 and 12 for engaging the same.

Within the upper portion of the tubular end bar 2 is arranged a vertical shaft 11^a, provided at its top with an arm 12^a, which is connected with the operating mechanism, and at a point between its ends the shaft carries a pair of diverging arms 13, which are connected with a reciprocating latch 14. The diverging arms 13 are connected with a threaded shank 15, extending through a horizontal slot 16 of the end bar 2, and when the shaft 11 is rotated in either direction the arms 13 retract the latch and disengage the same either from a keeper 17 of a main latch-post 18 or a keeper 19 of a supplemental latch-post 20, the gate being held in its open and closed positions to prevent it from accidentally closing when a vehicle is passing through the gateway.

The reciprocating latch consists of a rod guided on the gate and having its outer end provided with a return-bend, forming a loop and guided on the front end bar. This rod is provided with front and rear stops 21 and 22. The stop 22 engages the front end bar and limits the outward movement of the latch, and the inner stop 21 forms a bearing for a spring 23, which also abuts against one of the vertical bars 3, whereby the latch is rendered spring-actuated and is maintained in engagement with the keepers.

The arms 12^a and 13 are shown extending, respectively, in rear and in advance of the rear end bar 2 of the gate; but they may be reversed, if desired. The arm 12^a is connected by a wire 24 or similar connection with a pair of levers 25, fulcrumed between their ends on uprights 26 and having their lower ends shaped into handles. The upper ends of the levers are connected by wires 27, carrying a coiled spring 28, which is attached to their inner adjacent ends to form a cushion to facilitate an easy opening and closing of the gate.

The invention has the following advantages: The gate, which is simple and comparatively inexpensive in construction, is supported by a ball-bearing, and the operating mechanism is cushioned and is adapted to open and close the gate by a single oscillation

of the operating-levers. The bearing is dust and water proof, and the arms of the shaft, which are connected, respectively, with the operating mechanism and the latch, may be 5 reversed.

The arms 13 are connected with the inner end of the latch by a pair of chains 29, and the shaft 11 is provided with an annular flange 30, forming a cap or hood and extending over 10 the upper end of the bar 2 and adapted to shed water and prevent the same from entering the bearing.

Changes in the form, proportion, and minor details of construction may be resorted to 15 without departing from the spirit or sacrificing any of the advantages of this invention.

What is claimed is—

1. In a device of the class described, the combination of a swinging gate having a tubular end bar, a shaft journaled therein, a 20 latch connected with the lower portion of the shaft, and operating mechanism connected with the upper portion of the shaft and adapted to rotate the same, whereby the latch is 25 operated and the gate is opened and closed, substantially as described.

2. In a device of the class described, the combination of a swinging gate having a tubular end bar provided with a slot, a spring- 30 actuated latch mounted on the gate, a shaft journaled in the tubular end bar, a pair of arms connected with the shaft through the said slot and also connected with the latch, and operating mechanism for rotating the 35 shaft, substantially as described.

3. The combination of a gate having a tu-

bular end bar, a support provided with an upper eye and having a lower ball-cup receiving the gate, balls arranged within the cup, a bearing-cone mounted within the end bar and 40 arranged upon the balls, and a pintle fixed to the cup and extending through the bearing-cone, substantially as described.

4. The combination of a support having a ball-cup, balls arranged therein, a gate having a tubular end bar receiving the cup and 45 provided with a bearing-cone arranged upon the balls, a shaft journaled within the upper portion of the tubular end bar and provided with a cap covering the same, a latch connected with the shaft, and operating mechanism for rotating the latter, substantially as 50 described.

5. The combination of a gate having a tubular end bar, a shaft journaled therein and 55 provided with upper and lower arms, a latch connected with the lower arms, a pair of operating-levers fulcrumed on suitable supports at points between their ends, and the upper and lower connections between the levers, the 60 upper connection being provided with coiled springs and the lower connection being attached to the upper arm of the shaft, substantially as described.

In testimony that I claim the foregoing as 65 my own I have hereto affixed my signature in the presence of two witnesses.

UNION A. GREGG.
